SLEEPING CAR ARRANGEMENT

John W. Patton, Philadelphia, Pa., assignor to
 Edward G. Budd Manufacturing Company,
 Philadelphia, Pa., a corporation of Pennsylvania

Application December 6, 1938, Serial No. 244,148

5 Claims. (Cl. 105—315)

This invention relates to sleeping car arrangements, and more particularly to a novel arrangement of sleeping car compartments.

It is an object of the invention to provide a more economical use of the space without sacrifice of accessibility to the facilities usually provided and to provide an arrangement having a maximum of convenience and being variable to suit varying demands of the traveling public.

5 The above and other objects are attained according to the invention by arranging the sleeping compartments, each preferably intended for single occupancy, along one side of the car extending from a side aisle to the opposite side of the car, the longest dimension of the compartments extending transversely of the car from the side aisle to the opposite side of the car, and being provided at the aisle side with a vertical recess adapted to receive a fully-made-up folding bed 10 in inoperative position for day-time service. Each compartment is of a width longitudinally of the car not substantially greater than the combined width of the bed and the toilet seat arranged alongside thereof so that the toilet may always 15 be available even when the bed is lowered to its operative position from its vertical inoperative position.

For greatest economy the compartments are arranged in pairs separated by a common wall, 20 which is of less length than the walls of the compartments opposite the common wall, and terminates a substantial distance short of the aisle. Between the short inner extremity of the common wall and the adjacent ends of the aisle walls of 25 the compartments, there are provided inclined door openings normally closed by doors which permit separate access to each of the pair of compartments. By this arrangement, a recess is provided between each pair of compartments 30 adjacent the door openings, which facilitates the passage through the aisles and also serves to receive at certain times, the shoes or luggage of the occupants, as desired. By this arrangement the toilet facilities are provided in each compartment adjacent the common wall and in the corner 35 opposite the aisle alongside a window, while when the bed is lowered to its operative position, adequate floor space for dressing and undressing is provided between the toilet seat, the common wall, 40 the door and the side of the bed. It will thus be seen that this arrangement provides complete privacy for the occupants, and, at the same time, uses the space very economically without unduly cramping the movements and comfort of the 45 occupants.

Other and further objects and advantages, and the manner in which they are attained will become apparent from the following more detailed description in which reference will be had to the drawing forming a part thereof.

In the drawing:

Figure 1 shows diagrammatically and in horizontal sectional plan, a portion of a sleeping car embodying the invention.

Figure 2 is a diagrammatic vertical transverse 10 sectional view through one of the compartments with parts broken away.

Figure 3 is a detail view illustrating one manner of mounting the door to one of the compartments.

The invention is shown applied to a sleeping car, the body of which is represented generally by the numeral 10. The car is provided with a usual side aisle 11 along one side thereof, and the compartments, as 12 and 13, are preferably 20 arranged in pairs, and extend from the side aisle 11 to the opposite side of the car body. It is more economical of space, and the objects of the invention are more fully realized by arranging the two adjacent compartments 12 and 13 so that 25 they are symmetrically arranged with respect to the common wall 14 between them.

The greatest dimension of each compartment extends from the side aisle 11 to the opposite side wall of the car and for night time occupancy, as 30 shown in connection with the compartment 13, the movable bed 15 extends horizontally along the wall 16 opposite the common wall separating the compartments. At such times, a foldable chair 17 shown in compartment 12 in operative 35 position is folded and received under the bed 15. For day-time occupancy, as shown in connection with compartment 12, the bed 15 is folded into a vertical recess 18 provided along the aisle wall of a compartment. To permit easy movement of 40 the bed from its operative position to its inoperative position or vice-versa, it is hinged at 19 (see Figure 2) to a short vertical partition 20 forming the lower portion of the front wall of the recess 18, and a spring 21 connected respectively to the 45 end of the bed and to the bottom of the recess serves to counter-balance the weight of the bed when it is in the lowered position so that it is the more easily moved from the lower operative position to the inoperative position. When the 50 bed is folded to its inoperative position, its bottom wall forms an extension of the front vertical wall 20 providing a smooth finished appearance to the aisle wall of the compartment for day-time 55 occupancy. Suitable means such as a latch 22,

may be provided to hold the bed in its inoperative position. It will be understood that various forms of folding beds could be used, and applicant does not desire to be limited to the specific form shown.

From the foregoing it will be seen that the aisle wall is of a thickness sufficient to house the folding bed when in its vertical position, and it is of a width longitudinally of the car sufficient only 10 to receive the width of the bed.

For the greater portion of its length transversely of the car, a compartment is of a width, as clearly appears from the drawing, not substantially greater than the combined width of the bed 15 15 and the toilet seat 19, the toilet seat being arranged alongside of the bed so that it is at all times available. Other facilities are provided in the corner formed by the common wall 14 and the outer wall of the car up to a window opening 23 20 (one opposite each compartment), such as a folding basin 24 arranged above the toilet seat and to the rear thereof, and a mirror 25 above the basin. Directly against the outside wall may be arranged a linen closet 26 closed by door 27.

25 By reference to Figure 1 it will be seen that a wide door opening is provided between the inner end 28 of the common wall between the compartments and the adjacent end 29 of the aisle wall, this door opening being inclined to provide 30 the desired width of opening and being normally closed by door 30. In order to control the movements of the door and to move it out of the way when in opened position, it is preferably made of two hinged sections 30a and 30b. One of 35 these, 30a, is hinged to end 29 of the aisle wall and is of a width approximately that of the thickness of said wall, while the other engages a recess in the end 28 of the common wall 14 and is provided with a suitable locking device (not shown). 40 The door is guided in its movements by having the free end of its section 30b provided with studs 31 at top and bottom, movable in top and bottom guides 32, so that, when the door is completely open, the two sections fold against each 45 other and against the end of the aisle wall, as shown in dotted lines as shown in Figure 1. The common wall 14 between the compartments is preferably also constructed of hinged sections which can be folded against each other and 50 flanking one of the doors of a pair of compartments 12 and 13, as indicated in Figure 1 in dotted lines, when it is desired to throw the pair of compartments 12 and 13 into one large compartment.

55 By reason of the thickened aisle walls and the hinging of the doors to the inner margins of the ends 29 of the thickened walls, a recess 33 opening into the aisle is provided, as shown in Figure 1, between the thickened aisle walls of the two 60 adjacent compartments and the doors 30. This recess has the advantage of providing a freer passage through the aisles and also serves as a space to receive, at certain times, the shoes and luggage of the occupants without obstructing the 65 aisle. At night, for example, the occupants can leave their shoes outside the doors in this space for cleaning by the porter. Also, luggage can be temporarily set into this space by the porter where it does not obstruct the aisle.

70 As shown in Figure 1, supports 34 and 35 are provided to support the bed in its lowered position although other suitable forms of support may obviously be utilized.

Further facilities may be provided, as shown 75 in Figure 2, by providing a mirror 36 on opposite

sides of one of the sections of the common partition wall 14. The air-conditioning may be taken care of by an entrance grill 37 and an exit grill 38, the entrance grill being suitably connected to the air-conditioning duct extending the length of the car, which may, in this case, be arranged over the aisle as indicated at 39. A luggage rack 40 is provided in each compartment over the window opening 23 in its outer wall.

From the foregoing description and the disclosure in the drawing, particularly by reference to the showing in the plan view of Figure 1 it will be seen that the toilet facilities are at all times available, even when the bed is in its lowered position, and a very substantial floor space is free 15 for dressing and undressing. With this arrangement of individual sleeping compartments, the number of passengers that can be accommodated with complete privacy for each on a single car is greater than has heretofore been possible by 20 any arrangement of which applicant is aware which afforded the same degree of privacy and the same degree of constant availability and convenience of all the facilities provided in the compartment.

25 It will be understood, of course, that changes may be made in the details without departing from the spirit of the invention, and applicant does not desire to be limited in the scope of his invention beyond that required by the language 30 of the claims appended hereto.

What I claim is:

1. In a sleeping car having a side aisle, a compartment readily convertible into a bedroom with a bed extending horizontally along a transverse wall thereof or into a sitting room with the bed folded into the aisle wall thereof and a freely movable chair therein, and, when converted into a sitting room, having substantially its entire floor area available as full height standing room 40 said compartment having its longest dimension, as seen in plan, extending transversely of the car from the aisle to the opposite side of the car and having a width for the greater portion of its length not substantially greater than the combined width of said bed and a toilet seat arranged to be at all times available alongside the bed, the compartment having its aisle wall thickened and having a recess in said thickened wall arranged to receive the folding fully-made-up bed therein 50 for daytime occupancy with its bottom face flush with the inner face of the thickened aisle wall, the aisle wall being of a length for the height of a doorway opening just sufficient to receive said bed and the transverse wall at the side of a compartment adjacent said toilet seat terminating a substantial distance short of the aisle, an inclined wall including a doorway normally closed by a door extending from the inner margin of the adjacent end of said thickened aisle wall to 60 the adjacent end of said last-named transverse wall, and a door having sections hinged together and to the inner margin of said thickened aisle wall end, the sections being foldable against each other and against the end of the thickened aisle 65 wall when the door is open, thereby leaving the entrance passage to the compartment and the aisle unobstructed.

2. In a sleeping car having a side aisle, a pair of compartments each readily convertible into 70 a bedroom or a sitting room with a freely movable chair therein, and, when converted into a sitting room, having substantially its entire floor area available as full-height standing room said compartments each having a thickened aisle wall 75

having a recess therein arranged to receive a fully-made-up folding bed therein with its bottom face flush with the inner face of the thickened aisle wall for daytime occupancy and being 5 of a width not substantially greater than the combined width of said bed and a toilet seat arranged to be at all times available alongside of the bed, the aisle wall for the height of a doorway opening being of a width just sufficient to 10 receive said bed, a common wall separating said compartments terminating short of the aisle wall, and inclined doorways normally closed by doors provided between the inner margin of said thickened aisle walls and the common wall separating 15 the compartments, whereby a deep and wide recess communicating with the aisle and located between the adjacent ends of the thickened aisle walls is provided, the doors for said doorways comprising sections hinged together and to the inner margins of said thickened aisle wall ends, respectively, the sections of each door being foldable against each other and against the thickened end of the adjacent aisle wall, thereby leaving the entrance passage and aisle 20 unobstructed.

3. In a sleeping car having a side aisle, a compartment readily convertible into a bedroom with a bed extending horizontally along a transverse wall thereof or into a sitting room with the bed 25 folded into the aisle wall thereof and a freely movable chair therein, and, when converted into a sitting room, having substantially its entire floor area available as full height standing room, said compartment having its longest dimension, 30 as seen in plan, extending transversely of the car from the aisle to the opposite side of the car and having a width for the greater portion of its length not substantially greater than the combined width of said bed and a toilet seat 35 arranged to be at all times available alongside the bed, the compartment having its aisle wall thickened and having a recess in said thickened wall arranged to receive the folding fully-made-up bed therein for daytime occupancy with its 40 bottom face flush with the inner face of the thickened aisle wall, the aisle wall being of a length for the height of a doorway opening just sufficient to receive said bed and the transverse wall at the side of the compartment adjacent said 45 toilet seat terminating a substantial distance short of the aisle, and an inclined wall including a doorway normally closed by a door extending from the inner margin of the adjacent end of said thickened aisle wall to the adjacent end 50 of said last-named transverse wall.

4. In a sleeping car having a side aisle, a pair 55

of compartments each readily convertible into a bedroom or a sitting room with a freely movable chair therein, and, when converted into a sitting room, having substantially its entire floor area available as full-height standing room said 5 compartments each having a thickened aisle wall having a recess therein arranged to receive a fully-made-up folding bed therein with its bottom face flush with the inner face of the thickened aisle wall for daytime occupancy and being 10 of a width not substantially greater than the combined width of said bed and a toilet seat arranged to be at all times available alongside of the bed, the aisle wall for the height of a doorway opening being of a width just sufficient to 15 receive said bed, a common wall separating said compartments terminating short of the aisle wall, and inclined doorways normally closed by doors provided between the inner margin of said thickened aisle walls and the common wall separating 20 the compartments, whereby a deep and wide recess communicating with the aisle and located between the adjacent ends of the thickened aisle walls is provided.

5. In a sleeping car having a side aisle, a pair 25 of compartments each readily convertible into a bedroom or a sitting room with a freely movable chair therein, and, when converted into a sitting room, having substantially its entire floor area available as full-height standing room, said 30 compartments each having a thickened aisle wall having a recess therein arranged to receive a fully-made-up folding bed therein with its bottom face flush with the inner face of the thickened aisle wall for daytime occupancy and being 35 of a width not substantially greater than the combined width of said bed and toilet facilities arranged to be at all times available alongside of the bed, the aisle wall for the height of doorway opening being of a width just sufficient to 40 receive said bed, a common wall separating said compartments terminating short of the aisle wall, and inclined doorways provided between the inner margins of said thickened wall ends 45 and the adjacent end of the common wall separating the compartments, doors for closing said openings hinged to said aisle walls, the common wall having movable sections hinged together and to a fixed end portion flanking the door openings and movable to inoperative position 50 folded against each other and in flanking relation to a doorway of one of said compartments, whereby to convert the two compartments into one and move the said hinged section into an out-of-the-way location.

JOHN W. PATTON.
